UNITED STATES PATENT OFFICE.

JOHN G. BAKER AND THOMAS HENRY ASBURY, OF PHILADELPHIA, PENNSYLVANIA.

DESIGN FOR A FRAME FOR LAWN-SPRINKLERS.

SPECIFICATION forming part of Design No. 22,190, dated January 31, 1893.

Application filed August 21, 1890. Serial No. 362,682. Term of patent 14 years.

To all whom it may concern:

Be it known that we, JOHN G. BAKER and THOMAS HENRY ASBURY, citizens of the United States, both residing in Philadelphia, Pennsylvania, have invented a new and original Design for a Lawn-Sprinkler, of which the following is a specification.

Our design for a sprinkler frame is fully illustrated in the accompanying drawing, which represents the sprinkler frame in perspective.

The leading feature of the design is the **H**-form sprinkler frame having a standard projecting vertically therefrom.

A is the base of the sprinkler having two longitudinal portions and one transverse portion tying the two longitudinal portions together, the whole being in the form of an **H**.

We claim:

Design for sprinkler frame, said design consisting of the **H**-form base **A** and standard **B** projecting vertically therefrom, as described, and as shown in the annexed drawing.

In testimony whereof we have signed our names to this specification in the presence of two subscribing witnesses.

JOHN G. BAKER.

THOMAS HENRY ASBURY.
